LOUNGE CHAIR

Frank J. Luketa, Seattle, Wash.

Application July 12, 1946, Serial No. 633,185

3 Claims. (Cl. 155—105)

1

The present invention concerns a chair, where-
in a seat and a back are each tiltable relative to
the other between positions which may be de-
scribed as generally upright, and positions which
are generally horizontal, and which in addition
has a leg rest adjustable in and out and up and
down with respect to the seat which supports it,
a head rest adjustable with respect to the back
which supports it, and which has various other
accessories, such as a retractable table, a dis-
mountable reading stand, a storage compartment
in the arm, and the like. Briefly stated, the chair
of the present invention is a lounge chair adapted
to be adjusted into various positions, and having
immediately available various comforts and the
like for the use or convenience of the occupant.

The chair of the present application is related
generically to the chairs of various copending ap-
plications filed by me, and patents issued thereon,
as follows:

Serial No. 583,246, filed March 17, 1945, now aban-
doned,

Patent No. 2,481,133, dated September 6, 1949,

Serial No. 615,432, filed September 10, 1945,

Patent No. 2,491,898, dated December 20, 1949,

Serial No. 632,730, filed December 4, 1945, now
abandoned, and

Serial No. 647,153, filed February 12, 1946, now

Patent No. 2,514,655, granted July 11, 1950.

In its external aspects it is related also to certain
design patents issued to me as follows: 147,463 on
September 9, 1947; 149,959 and 149,429, both on
April 27, 1948.

The objects of the present invention are, in
general, the applicable objects stated in each of
the specifications referred to above. More spe-
cifically the present invention has for its object
the provision of a chair of this general nature,
best suited in construction and arrangement to
the achievement of the general objects indicated
above.

In the accompanying drawings the invention is
shown embodied in a typical and presently pre-
ferred form.

Figure 1 is a plan view of such a chair, with
parts broken away, and with the several parts
shown more or less in a recumbent position of
adjustment.

Figure 2 is a view in side elevation, broken
away, however, to show details of the head rest
operating mechanism and of the back operating
mechanism.

Figure 3 is a view similar to Figure 2, but bro-
ken away to show details of the seat operating

mechanism and of the leg rest operating mecha-
nism, and showing also certain auxiliary devices
incorporated in the chair.

Figure 4 is a broken-away rear view of the
back, showing the head rest operating mecha-
nism.

The remaining figures show various details.
Figure 5 is a view in the nature of a side eleva-
tion, or section at 5—5 of Figure 1, illustrating
motor cut-out means interconnecting the seat and
back. Figure 6 is a cross section through the arm,
illustrating the retractable table. Figure 7 is a
similar cross section of the arm, illustrating the
mount for the reading stand. Figure 8 is a plan
view of an arm, broken away to show the re-
tractable table, and other details. Figure 9 is a
cross section through the seat to show the man-
ner of connecting the seat tilting means to the
seat. Figure 10 is a detail section of one of the
supporting feet, and Figure 11 is a detail axial
section through the mount for the reading stand
showing the manner of supplying thereto current
for the reading lamp, this view being a section
on line 11—11 of Figure 3.

25 The seat 1 and the back 2 constitute principal
body supporting elements, and are pivotally
mounted for tilting about a common pivot axis
which lies in the vicinity of the rear edge of the
seat and the lower edge of the back. The arms 3
30 are part of the floor-engaging supporting frame,
and are connected across from side to side by
tubular braces 30. The leg rest 4 and the head
rest 5 are auxiliary body supporting members,
and in this construction the leg rest 4 is sup-
35 ported from and for movement with respect to
the seat 1, while the head rest 5 is similarly sup-
ported upon and for movement with relation to
the back 2.

The floor-engaging supporting frame, referred
40 to above, includes a pair of upright panels 31
connected by the cross braces 30, and the arms 3
are hollow and encase the panels 31 and the
mechanism supported thereupon. The frame as
a whole is supported upon feet 32, self-adjusting
45 to floor inequalities by a ball and socket connec-
tion at 33 to the cross braces 30 (see Figure 10).

The seat and the back are pivoted about co-
axial pivot supports which are carried by the
frame. A tubular rock shaft 20 supports the
50 back 2 by means of radial arms 21, disposed be-
side the hollow arms 3 and secured to the side
edges of the back. The tubular rock shaft 20
surrounds and is in part supported by an inner
rock shaft 10, which is connected to the frame-
55 work of the seat 1 by means such as the post or

pin 11 mounted in the hub 12 and projecting through a slot 22, of some circumferential extent, in the rock shaft 20 (see Figure 9). The rock shaft 10 may be, and preferably is, tubular, and surrounds and rocks about a tie rod 34, which joins the panels 31 at opposite sides of the frame, and which is readily demountable from the panels.

The rock shaft 10, and hence the seat 1, is tiltable by means of a worm quadrant 13 driven by a worm pinion 14 from a reversible motor 19 carried by one of the panels 31 within the arm at one side of the chair. The motor 19 is operated under control of switch buttons 39 arranged conveniently to the occupant in one of the arms of the chair, as is clear in Figure 3. In similar fashion the rock shaft 20, and hence the back 2, is tilttable by means of a quadrant 23 driven by a worm pinion 24 from a motor 29 carried upon one of the panels 31, normally the panel opposite that which supports the motor 19. The particular drive means described is simply representative of any suitable drive means that may be employed for tilting either the seat or the back.

The tilting movement of the seat need never be beyond a horizontal limit and an uptilted limit somewhat less than vertical; the tilting of the back, likewise, need never exceed vertical and horizontal limits, respectively. Relative movement of the seat and back through 90° will permit both to lie in a horizontal position, and will also permit the seat or the back to rise, relative to the other in horizontal position, to a precisely upright position. Ordinarily, the most comfortable position is one wherein the seat is somewhat uptilted above horizontal, and the back is tilted back from the vertical. The seat and the back do not ordinarily approach one another closer than 90°, hence it can be seen that if the slot 22 has an angular extent of approximately 90°, the seat and back will be permitted as much relative angular movement as is ordinarily desirable. Should an additional range of relative angular movement be desired, the slot 22 may be extended.

Since it is intended that the seat and back shall never tilt relatively closer than 90°, and the slot 22 is arranged to permit approach to this extent, but not closer, there remains the possibility that approach closer than this limit angle may tend to occur accidentally or through carelessness. Such jackknifing would probably produce structural damage, and certainly interference between parts.

To prevent this switches 15 and 25 are interposed in the control circuits of the respective motors 19 and 29, and are so located and arranged that relative approach of the seat and back closer than the intended limit angle of approach will break the motor circuit through one or both said switches, and approach movement will cease before damage occurs. The arrangement shown mounts a common switch-opening member 26 (Figure 5) upon the tubular shaft 20, to move relatively to both the switches 15 and 25 upon the rock shaft 10 in a path such that as the limit angle of approach is reached the member 26 depresses and opens both switches 15 and 25. An alternative arrangement would be to mount one switch upon the shaft 20 and the other upon the shaft 10, movable in paths to engage each the other.

The leg rest 4 is pivotally mounted at 40 upon supporting arms 41, one at each side, entering slots in the under side of the leg rest, and by this

means the leg rest is movable in and out with respect to the seat 1 which supports it, and up and down with respect to the seat. The leg rest is weighted, so that, hanging free as shown in full lines in Figure 3, it assumes a position nearly parallel to the front edge of the seat, against which it may retract. The supporting arms 41 are each pivoted at 42 to a nut 43, which is threaded upon and movable lengthwise of a jack screw 44 journaled in the framework of the seat 1. Each screw 44 is disposed parallel to guide-ways 16, and a roller 45 upon the nut 43 is guided in the guides 16, both for the purpose of preventing rotation of the nut 43 and for the purpose of affording a support for the pivot 42 in any position of the nut along its screw 44. Conjoint rotation of the two screws 44 is suitably accomplished, as by an endless chain 46 passing about sprocket wheels fast upon each of the screws 44, and driven by a sprocket wheel upon the shaft 47 from the motor 49.

Tilting of the leg rest is accomplished by up and down movement of guides such as the rollers 6, which engage beneath the arms 41 outwardly of all positions of the pivot 42. These guide rollers 6 are mounted upon levers 61 upon the rock shaft 60 journaled in and extending across the front edge of the framework of the seat. A quadrant 62 upon the rock shaft 60 receives a chain or similar tension member 63, which, in opposition to the spring 64 secured to the lever 65 on the rock shaft, rotates the rock shaft in such sense as to tilt the levers 61 upwardly, and thereby to elevate the leg rest 4. Such a pull on the chain 63 may be produced by rotation of a nut 66 upon a jack screw 67 from a motor 69 through the chain 68. A pin 67', projecting from the jack screw 67 and guided in a longitudinal slot, prevents rotation of the jack screw upon rotation of the nut. The rock shaft 60 and the jack screws 44 are so constructed in sections that they can be readily mounted or remounted in the chair.

The head rest 5 is analogous to the leg rest in that the head rest, like the leg rest, is an auxiliary body-supporting member, which is mounted upon and for movement with, but also for movement with respect to, the primary body-supporting member, which in the case of the head rest is the back 2. The head rest 5 is pivotally or hingedly supported by the elongated hinge 50 upon the upper edge of the back, and is engaged from its lower or rear side by a link 51 pivoted at 52 to the nut 53, which, being guided upon the guides 54 for rectilinear movement lengthwise of the back, is caused to move in this manner by rotation of the jack screw 55. Rotation of the jack screw, journaled in the framework of the back, is accomplished from a motor 59 through a chain drive 56. Limit switches 57 and 58 are disposed in the path of the nut 53, and are connected in the circuit to the motor 59 to break the circuit to the motor upon the nut reaching or approaching the respective limits of its movement.

While limit switches are not shown in conjunction with the other motors, other than the switches 15 and 25, it will be understood that such limit switches may be employed, as good practice dictates, in any place where their use would be helpful or convenient.

Such a chair would normally include, or provide the possibility of including, a reading stand for supporting reading matter conveniently to the occupant in any of the various positions that

he might desire to assume. Such a reading stand is suggested by the arm 7. In particular such a reading stand should be readily removable at will, and yet it should incorporate a reading lamp, so that dismounting of the reading stand involves disconnecting the circuit to the reading lamp. Moreover, such a connection must leave the reading stand freely adjustable with respect to the arm 3 which supports it. The arm 7 has been shown as provided with a downwardly projecting post 70 receivable within a socket 37 in the arm 3, and as is shown in Figure 11, the electric leads 71 within the post 70 and leading to the reading lamp terminate in circumferentially disposed contact rings 72, which engage within the socket 37 contactors 73 in an external circuit which feeds the reading lamp. The post 70 can be lifted out of the socket 37, which will disconnect the circuit, yet without the necessity of disconnecting wires, and reconnection is just as simply made by reinserting the post 70 within the socket 37. The construction and arrangement of the reading stand may vary widely, and any convenient form of stand may be employed.

All the controls for the several motors are 25 preferably concentrated in one of the arms 3 of the chair conveniently to the hand of the occupant, in whatever position of adjustment the chair may be. In consequence it is necessary that certain leads extend through from one arm to the other. To conceal the wires to the greatest degree possible, some of them extend from side to side of the chair through the tubular cross braces 38, as may be seen, for example, in Figures 2 and 3.

For the convenience of the occupant, it is desirable to provide a table, but on the other hand, it is not desirable that this table occupy any adjoining floor space, nor that it be visible at such times as it is not required. Accordingly I have provided a retractable table 8, pivoted at 28 upon an upright pivot, and projectable and retractable through a slot 38 in the exterior wall of the arm 3. Such a table is conveniently of semicircular shape, but when retracted it blends with the design of the chair; see Figures 6 and 8. In addition to the table it is also convenient to provide a compartment or recess 35 within the arm for the storage of articles which may be desired by the occupant, such as smoking materials. Such compartment is normally closed by a hinged cover 36.

In the arm opposite that one in which the reading stand is socketed, an ash tray 37' is provided, as well as an electric cigarette lighter and pushbutton controls 39 for a radio (not shown) which is also located in arm 3.

I claim as my invention:

1. A chair including as components a seat and a back, a tubular pivot support for one thereof, and a pivot support for the other extending coaxially through said tubular support, seat-tilting and back tilting means including rotative drive means operatively connected to the ends of the respective pivot supports, the connection between the inner pivot support and its supported chair component including an element extending through the tubular support transversely at a location between the latter's ends and support-

ingly engaging said supported component, said tubular support being circumferentially slotted for passage of said element, and to permit tilting of either the seat or the back independently and relatively to the other.

2. A chair including as components a seat and a back, a tubular pivot support for one thereof, and a pivot support for the other extending coaxially through said tubular support, seat-tilting and back tilting means including rotative drive means operatively connected to the ends of the respective pivot supports, the connection between the inner pivot support and its supported chair component including an element extending through the tubular support transversely at a location between the latter's ends and supportingly engaging said supported component, said tubular support being circumferentially slotted for passage of said element, and to permit tilting of either the seat or the back independently and relatively to the other, and means automatically operable upon relative approach of the seat and back to a minimum angle of approach to prevent further relative approach movement.

3. A chair including as components a seat and a back, a tubular pivot support for one thereof, and a pivot support for the other extending coaxially through said tubular support, seat-tilting and back tilting means including rotative drive means operatively connected to the ends of the respective pivot supports, the connection between the inner pivot support and its supported chair component including an element extending through the tubular support transversely at a location between the latter's ends and supportingly engaging said supported component, said tubular support being circumferentially slotted for passage of said element, and to permit tilting of either the seat or the back independently and relatively to the other, and cooperating means, one tiltable with the seat and another having a predetermined angular relationship to the first, tiltable with the back, in coincident paths, operatively connected to the seat-tilting and back-tilting means, engageable by relative approach of the seat and back to a predetermined minimum angle of approach, and when so engaged operable to deenergize the then energized tilting means.

FRANK J. LUKETA.
